HOLLOW FILLING AND/OR TRANSFUSION NEEDLE

Leo J. Novak and Marion D. Ford, Dayton, Ohio, assignors to The Commonwealth Engineering Company of Ohio, Dayton, Ohio, a corporation of Ohio

Application April 10, 1952, Serial No. 281,586

2 Claims. (Cl. 128—221)

This invention relates to the filling and emptying of containers useful in the art of transfusion of sterile materials such as blood plasma, blood, and blood volume expanders. More particularly, the invention relates to the hollow needles useful in the process.

Sterile materials to be transported are normally stored in sterile containers and are secured and permanently sealed with a high quality thick rubber stopper to prevent ingress of air to the bottle. To withdraw liquid from such a container a hollow needle having a very sharp point on one end thereof is passed through the stopper, while the other exposed end of the hollow needle is secured to the apparatus to which the material is to be transferred.

In the filling of this type of bottle it is customary commercial practice for one manufacturer to sterilize, evacuate and seal the bottle with a rubber cap and forward it to the producer of the liquid material for the filling of the bottles. When such bottles are to be filled the outer end of the needle is secured to the source of liquid which is to be placed in the bottle and the sharpened needle end is then passed through the rubber stopper and the liquid forced into the evacuated container. After filling the needle is withdrawn and the high quality rubber stopper closes over the small opening caused by the entrance of the needle, again sealing the bottle. Where required additional sealing means may be applied to the opening in the rubber.

A prime difficulty in the filling of these bottles has been that rubber particles are dislodged from the body of the rubber stopper as the needle passes therethrough and these particles find their way into the sterile liquid. When such a circumstance occurs, which is not infrequent, it is necessary to discard the contaminated material.

It has now been found that if a needle is provided having a long cutting edge and a relatively small bearing surface in contact with the body of rubber as the needle passes therethrough, that the possibility of rubber particles entering the sterilized material is substantially eliminated, and it is accordingly a primary object of this invention to provide a hollow needle having these characteristics.

It has also been found that it is particularly desirable in the filling of bottles that the hollow needle should preferably only enter the rubber body to an extent sufficient to insure that vacuum conditions are maintained, and accordingly it is another object of this invention to provide a new method for the filling of the bottles.

The needle of invention as noted should have a particularly long cutting edge and the cutting edge should form with the shank of the needle a very small angle, not greater than 12 degrees, and preferably not lower than 4 degrees. An angle of about 7 to 8 degrees has been found most suitable for the general purposes of this invention.

The invention will be more fully understood by reference to the following detailed description and the accompanying drawings wherein:

Figures 1 and 1a, respectively, are front elevational

2

and side elevational views illustrating the needle of invention;

Figure 2 is a sectional view illustrating the needle of invention when it is passed through the stopper of the bottle referred to hereinbefore;

Figure 3 is a view taken on line 3—3 of Figure 2; and

Figure 4 is a schematic view illustrating the apparatus for the filling of the bottles.

The needle of invention is illustrated in Figures 1 and 1a wherein the hollow needle 21 is provided with the usual stepped portions 22, 23 and 24 and an upper portion 25, while the cylindrical shank portion 26 is cut away as at 27 in Figure 1a to provide a cutaway portion comprising long cutting edges 27, 29 tapering inwardly and downwardly from the hollow cylindrical shank portion to a common piercing point, and a full-length portion lying between the edges and in the same plane as the wall of the cylindrical portion of which it is a continuation. Numeral 28 indicates the piercing point of the needle.

As may be clearly seen from Figure 2, when the needle having a shank 26 is passed through a rubber stopper, cutting of the rubber will take place substantially over the complete length of the passage and very little frictional resistance will occur. The cutting of the rubber by the edges 27, 29 evidently permits the rubber internally of the stopper to separate cleanly and due to its natural resilience to flow around the edges 27, 29 and partially into the hollow channel 32 of the needle 21. This latter arrangement is most clearly seen in Figure 3.

Since the portion 30 of the rubber which extends into the channel 32 has not been subjected to any scraping action whatsoever the liquid as it courses through the channel 32 will not dislodge particles and accordingly the liquid in the bottle will be free of such rubber material. While the upper cylinder portion of the needle 21 does, as indicated at 34 in Figure 5, enter the rubber stopper, as discussed more particularly hereinafter, and accordingly might be expected to engage in some dislodgment of particles, such has not been found to be the fact.

It will be noted in this connection that the total length of the cutting edges 27, 29, which taper inwardly and downwardly from the hollow circular portion of the shank to a common piercing point as indicated in Figure 2 is about 80% of the thickness of the stopper and the total length of the upper and lower shank portions is substantially the thickness of the stopper, the extent to which the completely cylindrical portion 26 enters the stopper being substantially equal in length to the distance which the needle shank 26 penetrates below the stopper into the bottle. Under this condition repeated experiments have established that substantially no rubber particles are dislodged.

In this connection it should be noted that the thickness of the rubber stopper and the needle length are related and that the resilience and abrasion resistance of the rubber of the stopper are factors.

When using stoppers of commerce having normal resilience, that is, those which will readily engage a bottle in air-tight relation, the optimum depth of penetration of the needle is approximately one-half the thickness of the stopper. With very thick stoppers the depth of penetration may, without deleterious effect, be increased if the cutting angle of the needle is maintained between about 4 to about 12°. Smaller angles than about 4° weaken a steel needle to such an extent that clean passage through the rubber is difficult while materially large angles do not provide the required cutting length and dislodgment of rubber particles results.

When using stoppers of very soft rubber, which abrade more easily, it is desirable that the needle penetrate

somewhat less than half the stopper thickness and the caution or limiting factor which must be observed in this respect is that the rubber engage the cylindrical portion of the needle in air tight relation. Fortunately the softer rubber will flow readily and such engagement may be accomplished easily. Thus the lower abrasion resistance of soft rubber is balanced by the higher resilience thereof.

Summarizing these factors it has been found that the depth of penetration of the needle should be such that at least .2 of the thickness of the stopper is penetrated by the completely cylindrical needle portion, a lower limit which prevails for soft rubber. For thicker stoppers not more than .8 of the thickness of the stopper should be penetrated by the completely cylindrical portion, a limit which prevails for normally resilient rubbers.

Accordingly it is clear that the length of the shank portion having the cutting edges must be of lesser length than a stopper with which it is associated, and preferably is not longer than 80% of the stopper thickness; the minimum cutting edge length which a needle may have would be determined by the requirement that the angle formed between the cutting edge portion and the full length wall portion of the needle be between about 4 to 12°; where the stopper thickness and material are such as to permit it a smaller angle than 4° may be used, but extreme care must then be taken to avoid bending of the needle as abrasion of the rubber wall would result therefrom.

Also the preferable form of the upper closed shank portion is a circle while the lower shank portion is in cross-section preferably a series of superposed minor circular arcs progressively decreasing in peripheral length and terminating in a needle point.

In many instances the rubber stoppers used in the art are not made of one component but have a central vertically extending portion of soft rubber surrounded by a peripheral portion of harder material. In such a case the above limitations apply to the central portion of rubber which is better adapted to pass the needle.

With the needle structure noted the needle diameter is not a critical factor but it is to be noted that for most commercial purposes the useful diameters lie between about $\frac{1}{16}$ to $\frac{1}{4}$ inch.

In order to completely illustrate the invention there is shown in Figure 4 a structure for the filling of the bottles and it will be noted that there is indicated generally at 300 a source of liquid material which flows through a rubber line 301, which flow may be shut off by stopcock 302. In the use of the stainless steel needle in connection with this source of supply the upper portion 25 is secured into the lower portion of line 301 while the stopcock 302 is closed. The steel needle is then passed through the rubber stopper 200 as indicated in Figure 5, the stopcock 302 opened and the liquid from source 300 flows into bottle 201. Upon completion of the operation of filling stopcock 302 is closed and the needle 21 is withdrawn from the stopper 200

in the bottle 201 and the stopper 200 substantially reseals itself. In given instances as where a needle has been used which is not quite sharp the stopper 200 may have additional sealing material provided therefor.

5 It will be understood that this invention is susceptible to modification in order to adopt it to different usages and conditions and accordingly, it is desired to comprehend such modifications within this invention as may fall within the scope of the appended claims.

10 We claim:

1. In combination, a resilient stopper for a container and a hollow needle disposed in the stopper for introducing liquid into the container through the stopper, said needle having an upper shank portion the cross-section of which is circular throughout and a lower shank portion integral therewith the progressive cross-sections of which are superposed minor circular arcs of progressively decreasing peripheral lengths terminating in a needle point, the upper and lower shank portions having a common wall portion and the extremities of the arcs forming cutting edges which lie in the same plane throughout their entire length and form an angle of 4° to 12° with said wall portion, the relative lengths of the upper and lower shank portions of the needle being such that the juncture therebetween is enclosed by the stopper at about the center of the thickness thereof and the distance to which the upper shank portion extends into the stopper is substantially equal to the distance to which the lower shank portion extends below the stopper into the container.

2. In combination, a resilient stopper for a container and a hollow needle disposed in the stopper for introducing liquid into the container through the stopper, said needle having upper and lower shank portions, the upper shank portion having a circular cross-section throughout and the lower shank portion having a cross-section which is an open curve progressively decreasing in peripheral length to a sharp point from the juncture of the upper and lower shanks, the upper and lower shanks having a common wall portion and the open curve being defined by opposed cutting edges which lie in the same plane throughout their entire length and form an angle of 4° to 12° with said wall portion, the relative lengths of the upper and lower shank portions of the needle being such that the juncture therebetween is enclosed by the stopper at about the center of the thickness thereof and the distance to which the upper shank portion extends into the stopper is substantially equal to the distance to which the lower shank portion extends below the stopper into the container.
